UNITED STATES PATENT OFFICE.

PAUL RECKOW, OF CHICAGO, ILLINOIS.

MACHINE FOR SETTING THE EDGE JOINTS OF VENEER STRIPS.

1,279,587.

Specification of Letters Patent. Patented Sept. 24, 1918.

Application filed December 3, 1917. Serial No. 205,227.

To all whom it may concern:

Be it known that I, PAUL RECKOW, a citizen of the United States, residing at Chicago, in the county of Cook and State of Illinois, have invented a certain new and useful Improvement in Machines for Setting the Edge Joints of Veneer Strips, of which the following is a specification.

My invention relates to a machine for setting the edge joints of veneer strips so that the edges of said strips may be glued together without leaving open spaces between them. My machine consists essentially of a base supporting a table comprising a plurality of sections movable relatively to each other and suitable clamping devices for holding strips of veneer upon the sections of the table so that the said strips of veneer are in substantially the same plane. My machine also contains devices for moving the sections relatively to each other to bring the edges of the strips of veneer closely into engagement with each other. I also provide in my machine, clamping strips for engaging the edge portions of the strips of veneer to hold them in alinement with each other, thus facilitating the making of close joints between them. I also find it desirable to supply the sections of the table with roughened surfaces affording a relatively high degree of frictional engagement with the strips of veneer, as a result of which movement of the table sections as described positively moves the strips of veneer into engagement with each other.

My invention will best be understood by reference to the accompanying drawings showing a preferred embodiment thereof, in which—

40 Figure 1 is a plan view of my machine, Fig. 2 is a side elevation of the machine shown in Fig. 1,

Fig. 3 is a longitudinal sectional view of the parts shown in Fig. 1, taken along the 45 line 3—3,

Fig. 4 is a transverse sectional view of the parts shown in Fig. 1, taken along the line 4—4,

50 Fig. 5 is a detail view of one of the clamping strips removed from the machine, this view being on a reduced scale,

Fig. 6 is a detail view of portions of two strips of veneer after being removed from the machine, and

Fig. 7 is a detail view of portions of two strips of veneer after being secured together in the machine in the position they occupied during the subsequent gluing operation.

Similar numerals refer to similar parts throughout the several views.

As shown in the drawings, my machine consists of a base 10 upon which there are mounted table sections 11, 12 and 13, these sections extending longitudinally of the machine. The middle section 12 is rigidly secured to a longitudinal bar 14, which in turn is rigidly secured to the base 10. The sections 11 and 13 have rigidly secured to their under surface similar bars 15 and 16, 70 which however are not secured to the base. The bars 15 and 16 have secured to them transverse bars 17 and 18 respectively, which are also free from the base, and extend under the edges of the section 12, thus serving to 75 prevent the sections 11 and 13 from tipping out of the plane of the section 12. The bars 14 and 16 are connected together by transversely extending screws 19, which, as shown for one of said screws, extend through suitable nuts 20 rigidly held in place against the bar 14 by a block 21. Each of these screws is provided at the outer edge of the bar 16 with a groove 22 engaging a slot in a retaining plate 23 carried by the bar 16, as a result 80 of which when the screws 19 are turned by the handles 24 rigidly secured to the outer ends of said screws the bar 16 and parts carried thereby are moved toward or away from the bar 14 and the parts carried thereby depending upon the direction of rotation of said screws. The bar 15 is similarly secured to the bar 14 by screws 25 which serve in a similar manner to move the section 11 toward or away from the section 12 of the 85 table.

The sections 11, 12 and 13 of the table are so supported by and disposed upon the base 10 that their surfaces are in substantially the same plane, and over these table sections 100 clamping plates 26, 27 and 28 respectively are disposed for securely holding strips of veneer 29, 30 and 31 respectively against the supporting surfaces of the table sections. The table sections and the clamping plates 105 may be of any desired width and length to properly handle the strips of veneer to be fastened together and in any event the

clamping plates are somewhat narrower than the sections of the table, to leave clearances between said clamping plates for a purpose to be described.

5 The clamping plates 26, 27 and 28 are supported by the bars 15, 14 and 16 respectively and, since the manner of supporting each of said plates from the corresponding bar is the same, it is necessary to describe but one 10 of them, as for example the support of the clamping plate 28 from the bar 16. As shown in Fig. 2, the bar 16 has rigidly secured to its righthand end a metal strip 32 extending upwardly from the end of said 15 bar and to the upper end of this metal strip a clamping bar 33 is pivotally secured at 34. The other end of the bar 16 has pivotally secured thereto at 35 a second metal strip 36, to the upper end of which is pivotally connected at 37 a cam 38, provided with an operating handle 39. The lefthand end of the bar 33 is slotted to receive the metal strip 36 when the parts are in the position shown in Fig. 2. The bar 33 is secured to the 20 clamping plate 28 by means of two screws 40 which fit loosely in holes therefor formed through bar 33, and between the bar 33 and the clamping plate 28 springs 41 are disposed which exert a pressure upon the 25 clamping plate 28 in a direction away from the bar 33.

Over the adjacent edge portions of each pair of table sections clamping strips 42 and 43 are disposed and, since these are 30 similar in their construction and operation, it is necessary to describe but one of them as, for example, the clamping strip 42. As more clearly shown in Fig. 3, the strip 42 is held in position at one end by a hook 44 35 rigidly secured to the base and at the other end is a hook 45 pivotally secured to the base at 46. The clamping strip is made of elastic or spring material, such as wood or metal, and when free from restraint is 40 curved or bent from a straight line from end to end, as shown in Fig. 5. In making these clamping strips from wood, I find it desirable to saw them in the curved shape indicated so that they may retain their tendency 45 to assume said curved position instead of forming them by bending them from straight pieces of wood since the latter would in time tend to straighten out and lose their effectiveness for the purpose desired. The strip 42 is provided with a handle 46' for moving the lefthand end of the strip shown in Fig. 3 to a position permitting it to be engaged by the pivoted hook 45.

In using my machine, the cams and the 60 pivoted metal strips are moved to their releasing position, the clamping plates are moved away from the table sections by moving their supporting bars on their pivotal supports and the clamping strips are removed

by disengaging them from the corresponding pivoted hooks. The strips of veneer 29, 30 and 31 are then placed upon the table sections 11, 12 and 13 respectively with the edges of said strips of veneer adjacent the openings between the table sections. The 70 clamping plates 26, 27 and 28 are then moved to the position indicated in the drawings and securely held in said positions by means of the cams referred to against the resisting action of the springs between the 75 clamping plates and their supporting bars. The screws 19 and 25 are then turned to bring the inner edges of the strips of veneer 80 in this position paper tape or equivalent material as indicated at 47 is glued over the joints between the strips of veneer, thus securely holding said strips of veneer with their edges closely together. The clamping 85 strips 42 and 43 are then put in place over the paper tapes as a precautionary measure to insure that the edge portions of the strips of veneer shall be held in substantially the same plane during the drying of the glue 90 holding the paper strips in place and also that the paper tapes shall be securely held against the portions of the strips of veneer engaged thereby.

To provide against the possibility of the 95 strips of veneer slipping on the table sections, I find it desirable to provide the table sections with roughened supporting surfaces or surfaces of roughened material as indicated at 11^a, 12^a and 13^a. In practice 100 I find that strips of sandpaper glued to the supporting surfaces of the table sections serve admirably for this purpose, although any equivalent material may be employed for securing a high degree of frictional engagement between the strips of veneer and the sections of the table, as for example strips of sheet rubber.

When the glue or other adhesive material holding the paper take in place has dried, 110 the strips of veneer are removed from the machine and are held together as indicated in Fig. 6 with their adjacent edges securely engaging each other to make tight and perfect joints between them. The strips of veneer are then placed in the relative position indicated in Fig. 7, which is permitted on account of the flexibility of the tape 47, and the edges may be glued after which the strips of veneer are moved into the same 115 plane and as a result of the manner in which the tape was applied to the strips the edges of the strips of veneer are again brought into close engagement with each other throughout the entire length of said strips and after the glue has dried with the strips of veneer held in the position indicated in Fig. 6, which may be done by any suitable

holding devices; it is found that the joints between the strips of veneer are so perfect as to be scarcely discernible.

While strips of veneer have been secured together heretofore by the use of paper tape and gluing, it has been extremely difficult with the mechanism employed to bring the edges of the strips of veneer closely and firmly into engagement with each other before applying the tape and my machine greatly simplifies this operation by making it unnecessary that the strips of veneer shall be in close engagement with each other when the clamping plates are brought into engagement with said strips of veneer in the machine, since the strips of veneer may readily and quickly be brought into close and firm engagement with each other while the strips are clamped in the machine and as a result the strips of veneer may be secured together very effectively and quickly and with as high a degree of perfection as is permitted by the material of the veneer and the condition of the edges of the veneer strips joined together.

While I have shown my invention in the particular embodiment described above, it will be understood that I do not limit myself to this exact construction, as I may employ equivalents thereof known to the art at the time of the filing of this application without departing from the scope of the appended claims.

What I claim is:

1. In a veneer joint setting machine, the combination of a base having a flat continuous upper surface, a first supporting bar extending longitudinally of the base and secured to the upper surface thereof, a first table section wider than said bar and secured to the upper surface thereof, a second bar similar to said first bar supported on the upper surface of said base in substantially parallel relation to said first bar, a second table section similar to said first table section secured to the upper surface of said second bar, two adjusting screws extending laterally and horizontally through the end portions of said bars, each of said screws being in threaded engagement with one of said bars, devices connecting each screw to the other bar and permitting rotation and preventing longitudinal motion of said screw relatively to said other bar, a clamping plate for holding a veneer strip on the upper surface of each table section, and a clamping strip between said clamping plates for holding the adjacent edge portions of said veneer strips in engagement with the upper surface of said table sections.

2. In a veneer joint setting machine, the combination of a base having a flat continuous upper surface, a first supporting bar ex-

tending longitudinally of the base and secured to the upper surface thereof, a first table section wider than said bar and secured to the upper surface thereof, a second bar similar to said first bar supported on the upper surface of said base in substantially parallel relation to said first bar, a second table section similar to said first table section secured to the upper surface of said second bar, two adjusting screws extending laterally and horizontally through the end portions of said bars, each of said screws being in threaded engagement with one of said bars, devices connecting each screw to the other bar and permitting rotation and preventing longitudinal motion of said screw relatively to said other bar, a clamping plate for holding a veneer strip on the upper surface of each table section, and a clamping strip between said clamping plates for holding the adjacent edge portions of said veneer strips in engagement with the upper surface of said table sections, said screws extending outwardly beyond the edge of said base, and handles secured to the outer ends of said screws for rotating the same.

3. In a veneer joint setting machine, the combination of a base having a flat continuous upper surface, a first supporting bar extending longitudinally of the base and secured to the upper surface thereof, a first table section wider than said bar and secured to the upper surface thereof, a second bar similar to said first bar supported on the upper surface of said base in substantially parallel relation to said first bar, a second table section similar to said first table section secured to the upper surface of said second bar, two adjusting screws extending laterally and horizontally through the end portions of said bars, each of said screws being in threaded engagement with one of said bars, devices connecting each screw to the other bar and permitting rotation and preventing longitudinal motion of said screw relatively to said other bar, a clamping plate for holding a veneer strip on the upper surface of each table section, and a clamping strip between said clamping plates for holding the adjacent edge portions of said veneer strips in engagement with the upper surface of said table sections, said clamping strip being of wood sawed in circular conformation, and devices for holding the ends of said strip against said veneer strips and thus holding said strip in straightened position exerting pressure upon the adjacent edge portions of said veneer strips.

4. In a veneer joint setting machine, the combination of a base having a flat continuous upper surface, two table sections supported on the upper surface of said base in substantially the same plane, a first one of

5 said sections being rigidly secured to said base and the other section being movable laterally upon said base relatively to said first section, means for moving said other 10 section relatively to said first section, a clamping plate for holding a veneer strip on the upper surface of each table section, and a clamping strip between said clamping plates for holding the adjacent edge portions of 15 said veneer strips in engagement with the upper surface of said table sections.

5. In a veneer joint setting machine, the combination of a base having a flat continuous upper surface, two table sections supported 15 on the upper surface of said base in substantially the same plane, a first one of said sections being rigidly secured to said base and the other section being movable laterally upon said base relatively to said 20 first section, means for moving said other section relatively to said first section, a clamping plate for holding a veneer strip on the upper surface of each table section, and a clamping strip between said clamping 25 plates for holding the adjacent edge portions of said veneer strips in engagement with the upper surface of said table sections, said clamping strip being of wood sawed in circular conformation, and devices for holding 30 the ends of said strip against said veneer strips and thus holding said strip in straightened position exerting pressure upon the adjacent edge portions of said veneer strips.

6. In a veneer joint setting machine, the combination of a base having a flat continuous upper surface, a first supporting bar extending longitudinally of the base and secured to the upper surface thereof, a first table section wider than said bar and secured 40 to the upper surface thereof, a second bar similar to said first bar supported on the upper surface of said base in substantially parallel relation to said first bar on each side thereof, a second table section similar to 45 said first table section secured to the upper surface of each of said second bars, two adjusting screws extending laterally and horizontally through the end portions of each of said second bars and said first bar, each of 50 said screws being in threaded engagement with one of said bars, a device connecting each screw to the other bar engaged by it and permitting rotation and preventing longitudinal motion of said screw relatively to 55 said other bar, a clamping plate for holding a veneer strip on the upper surface of each table section, and a clamping strip between the central clamping plate and each of the other clamping plates for holding the adjacent edge portions of said veneer strips in engagement with the upper surface of said table sections.

7. In a veneer joint setting machine, the combination of a base having a flat continu-

ous upper surface, a first supporting bar extending longitudinally of the base and secured to the upper surface thereof, a first table section wider than said bar and secured to the upper surface thereof, a second bar similar to said first bar supported on the upper surface of said base in substantially parallel relation to said first bar on each side thereof, a second table section similar to said first table section secured to the upper surface of each of said second bars, two adjusting screws extending laterally and horizontally through the end portions of each of said second bars and said first bar, each of said screws being in threaded engagement with one of said bars, a device connecting each screw to the other bar engaged by it and permitting rotation and preventing longitudinal motion of said screw relatively to 75 said other bar, a clamping plate for holding a veneer strip on the upper surface of each table section, and a clamping strip between the central clamping plate and each of the other clamping plates for holding the adjacent edge portions of said veneer strips in engagement with the upper surface of said table sections, said screws extending outwardly beyond opposite edges of said base, and handles secured to the outer ends of said screws for rotating the same.

8. In a veneer joint setting machine, the combination of a base having a flat continuous upper surface, a first supporting bar extending longitudinally of the base and secured to the upper surface thereof, a first table section wider than said bar and secured to the upper surface thereof, a second bar similar to said first bar supported on the upper surface of said base in substantially parallel relation to said first bar, a second table section similar to said first table section secured to the upper surface of said second bar, two adjusting screws extending laterally and horizontally through the end portions of said bars, each of said screws being in threaded engagement with one of said bars, devices connecting each screw to the other bar and permitting rotation and preventing longitudinal motion of said screw relatively to 95 said other bar, and a clamping plate for holding a veneer strip on the upper surface of each table section.

9. In a veneer joint setting machine, the combination of a base having a flat continuous upper surface, a first supporting bar extending longitudinally of the base and secured to the upper surface thereof, a first table section wider than said bar and secured to the upper surface thereof, a second bar similar to said first bar supported on the upper surface of said base in substantially parallel relation to said first bar on each side thereof, a second table section similar to said first table section secured to the upper sur-

face of each of said second bars, two adjusting screws extending laterally and horizontally through the end portions of each of said second bars and said first bar, each of 5 said screws being in threaded engagement with one of said bars, a device connecting each screw to the other bar engaged by it and permitting rotation and preventing longitudinal motion of said screw relatively to 10 said other bar, and a clamping plate for

holding a veneer strip on the upper surface of each table section, said screws extending outwardly beyond opposite edges of said base, and handles secured to the outer ends of said screws for rotating the same. 15

In witness whereof, I hereunto subscribe my name this 26th day of November, A. D. 1917.

PAUL RECKOW.
